UNITED STATES PATENT OFFICE.

CALVIN JACKSON, OF READING, PENNSYLVANIA.

LATHE-TOOL AND HOLDER.

SPECIFICATION forming part of Letters Patent No. 687,237, dated November 26, 1901.

Application filed March 1, 1900. Serial No. 6,937. (No model.)

To all whom it may concern:

Be it known that I, CALVIN JACKSON, a citizen of the United States of America, and a resident of Reading, in the county of Berks 5 and State of Pennsylvania, have invented certain new and useful Improvements in Lathe-Tools and Holders, of which the following is a specification.

My invention relates more particularly to 10 lathe-tool holders and cutters; and my object is to provide a simple, inexpensive, and easily-maintained form of cutter-tool in connection with a holder, and clamping means adapted to permit the ready adjustment of the cutter 15 to suit various conditions and the easy and convenient fastening or loosening of the same.

The invention is fully described in connection with the accompanying drawings, and the novel features are pointed out in the 20 claims.

Figure 1 is a side elevation, partly in section, 25 of my complete device in preferred form, the clamping-wedge being shown loosely in position. Fig. 2 is a plan view of the stock alone. Fig. 3 is an end view looking in the direction of the arrow, and Fig. 4 is a similar view showing the cutter adjusted rotatively from Figs. 1 and 3 position.

A represents a holder or stock, which is cut 30 from a rolled bar of steel of rectangular section, the parting cut being at such an angle as to form parallel end faces a^3 and a^5 , the former of which provides proper clearance below the cutter. The upper corner of the 35 outer end is cut away to a much greater angle, forming an inclined face a^2 , thus providing ample clearance for the chips and place for fastening and loosening the cutting-tool. Through this face a^2 opens a round receiving-hole a for this tool, said hole being drilled 40 rearward with a downward incline, as shown. Its inclined lower wall about meets the intersection of the oppositely-inclined end faces a^2 a^3 , and a reduced extension of it (marked 45 a') opens through the bottom of the stock, so as to permit of access from the rear.

The cutter B is designed to be made by 50 simply cutting off from a rolled bar of tool-steel, which may be readily produced, a proper length for a cutter and then grinding the end b to the desired shape. Its half-round cross-section is adapted to loosely fit the

round receiving-hole a of the stock. In order to adjustably secure it in the latter, a similar half-round filling-piece C is employed, 55 thus occupying the hole as fully as though the cutter were made out of a round bar, but avoiding the expensive and troublesome grinding which the latter form would necessitate, while at the same time making it possible to fasten and release the cutter far more 60 conveniently and satisfactorily than is practicable with a solid round cutter, as will clearly appear from the preferred means shown in the drawings.

Instead of employing one or more set-screws 65 engaging a screw-threaded hole or holes in the stock, as indicated at a^6 , which would serve the purpose with my two-part tool as well as it would with a solid round one, I am 70 enabled to employ with advantage a wedge-piece E between the half-round cutter and filling-piece. For this purpose I taper the forward end of the filling-piece so as to provide an inclined face c' , preferably terminating 75 in the normal flat face c some distance forward of the rear end of the filling-piece, so that the latter when inserted in the hole a with the cutter B will be positively held up at the front end so as to conveniently admit 80 the wedge-piece E. In adjusting the cutter either longitudinally or by turning it for right or left hand use, as indicated in Fig. 4, the wedge is withdrawn. When adjusted, it is forced into place, thus spreading the parts and 85 firmly clamping the cutter. When it is desired to loosen the latter, it may be accomplished as heretofore in similar devices by means of the previously-mentioned extension a' of the hole a through the base of the stock, which 90 permits of access to the rear end of the cutter. To provide for accomplishing this result more conveniently and satisfactorily, however, I provide a movable stop for the 95 rear end of the filling-piece C, against which it may bear while the wedge E is forced into place, but which will permit an inward movement of the filling-piece for the purpose of releasing the wedge when desired. This movable stop is preferably made in the form of a 100 yielding spring D, which bears against the square bottom a^4 of the hole a above the reduced bottom passage a' and which when the cutter is fastened by the forcing in of the

wedge will normally tend to press the filling-piece C outward, and thus make the fastening more secure. When it is desired to loosen the cutter, however, a moderate tap upon the 5 outer end c^2 of the filling-piece will cause the spring-stop D to yield and permit a momentary inward movement tending to release the wedge E, followed by a quick return tending to carry the loosened wedge outward. Two 10 or three such taps will serve to entirely loosen the parts so as to permit their free removal or readjustment.

The round receiving-hole for the cutter is not only easily formed by drilling, but it may 15 also be of a size little less than the thickness of the stock A without objectionably weakening the latter, the side walls being of minimum thickness only in the transverse axial plane of the hole. It also permits the use of 20 a wide-faced cutter B capable of rotary adjustment, whereby an extended cutting edge may be brought into service and the necessity for separate right and left shapes is dispensed with. The economy of first cost and 25 maintenance is important as is also the convenience in fastening and loosening the cutter.

What I claim is—

1. The combination with a tool holder or stock having a plain cylindrical receiving-hole, of a cutter of half-round cross-section fitting said hole, and clamping means located entirely in said cylindrical hole between the wall thereof and the flat face of said half-round cutter for adjustably securing said cutter 35 in the receiving-hole.

2. The combination with a tool holder or stock having a cylindrical receiving-hole, of a cutter of half-round cross-section fitting said hole, and clamping means comprising a separate filling-piece and a wedging device located 40 entirely in said cylindrical hole between the wall thereof and the flat face of said half-

round cutter for adjustably securing said cutter in the receiving-hole.

3. The combination with a tool holder or 45 stock having a cylindrical receiving-hole, of a cutter of half-round cross-section fitting said hole, a separate filling-piece of similar cross-section but tapered toward one end, and a wedge-piece fitted between said tapered filling-piece and the cutter and adapted to secure the latter in adjusted position.

4. The combination with a tool holder or stock having a cylindrical receiving-hole, of a cutter of half-round cross-section fitting said 55 hole, a separate filling-piece of similar cross-section having the forward portion only thereof tapered toward the outer end, and a wedge-piece fitted between said tapered filling-piece and the cutter and adapted to secure the latter in adjusted position.

5. The combination with a tool holder or stock having a cylindrical receiving-hole, of a cutter of half-round cross-section fitting said 60 hole, a separate filling-piece of similar cross-section but tapered toward the outer end, a wedge-piece fitted between said tapered filling-piece and the cutter, and a movable stop in said hole for the inner end of said tapered filling-piece.

6. The combination with a tool holder or stock having a cylindrical receiving-hole, of a cutter of half-round cross-section fitting said 70 hole, a separate filling-piece of similar cross-section but tapered toward the outer end, a wedge-piece fitted between said tapered filling-piece and the cutter and a spring-stop for the inner end of said tapered filling-piece.

Signed by me at Reading, Pennsylvania, this 26th day of February, 1900.

CALVIN JACKSON.
